UNITED STATES PATENT OFFICE

ARTHUR B. WALTERS, OF KANSAS CITY, MISSOURI, ASSIGNOR TO WESTERN TOOL & EQUIPMENT COMPANY, A CORPORATION OF MISSOURI

ADJUSTABLE LEVEL

Application filed May 21, 1928, Serial No. 279,355. Renewed April 13, 1931.

This invention relates to an adjustable level of convenient form for use by mechanics, carpenters or other workmen to determine the pitch or inclination of building or other structural elements in degrees, inches per foot, or in any other convenient units.

A further object of the invention is to produce a tool of the character described which is so constructed that it may be readily and easily set to a predetermined angle by registering the markings on a movable element with index marks on the frame, whereby the operator need then only bring the bubble in a spirit level to the center of its housing as common with all levels, to know that the base or straight edge of the tool is set to the desired angle with respect to the horizontal or vertical.

Another object of the invention is to provide an automatic frictional locking device to hold the adjustable part of the level at any desired setting, said lock being also manually adjustable to positively clamp and hold the moving member when many angles of the same degree are to be determined.

A still further object of the invention is to provide means whereby the spirit level may be adjusted as necessary to maintain proper relationship with the other parts of the tool.

With the general objects named in view, and others as will hereinafter appear, the invention consists in certain novel and useful features of construction and organization of parts as hereinafter described and claimed; and in order that it may be fully understood, reference is to be had to the accompanying drawings, in which:

Figure 1 is a side view of a level embodying the invention.

Figure 2 is a partial central longitudinal section taken through the level.

Figure 3 is a central vertical section through the level as shown in Figure 2.

In the said drawings, 1 indicates any suitable strong and durable framework, formed along one of its edges with a straight edge or operating face 2, it being evident that the framework and straight edge may be extended to any desired length, depending upon

the particular purpose for which the tool is designed.

The framework 1, preferably intermediate its ends, is formed with a central opening surrounded by a frame 3, said frame being 55 permanently marked adjacent its inner margin and on its opposite sides, with two pairs of index lines 4 and 5, respectively arranged in perfect parallelism and at an angle of ninety degrees to the base or straight edge 2. 60

Fitted accurately and rotatively within the frame 3 is a flat ring 6 formed on its opposite sides with a series of markings 7 and 8. The former is preferably marked from zero degrees to ninety degrees to the right and left respectively, and the latter from zero inches to twelve inches to the right and left respectively, to indicate inclination in degrees and in inches per foot, although it will be apparent that the scales may be marked 70 with any desired units or indicating indicia.

The ring 6 is formed with a central circumferential groove 9 in its outer face to receive the reduced end 10 of a threaded thumb set lock 11 carrying a ball 12 held by a spring 13 in frictional contact with the bottom of the slot or groove 9. Thus, the operator by changing the tension on the ball may insure the holding of the adjustable ring 6 in any desired position, it being remarked that if 80 a positive lock is desired, the thumb screw 11 may be threaded downwardly until its reduced end 10 contacts with the ring 6 and positively clamps same against rotation. Under actual working conditions, it is probable that the greater part of the time the device will be used as an ordinary spirit level or as a plumb level, and therefore, as a matter of convenience, the ring 6 is formed with 85 four recesses or holes 14 normally in alignment with the horizontal and vertical markings on the frame 3 into which the ball lock 12 may be projected to hold the ring in adjustment with a somewhat more secure hold than if said recesses were not provided.

Although it is believed the ring 6 will probably be properly held in position within the frame 3 by the reduced end 10 of the thumb set screw 11 received within the slot 9 of the ring, it is thought desirable to posi- 100

tively insure against accidental dislodgment by providing a pair of screws 15 carried by the frame 3, said screws having their ends received within the slot 9 as illustrated. It 5 will be evident a screw or auxiliary retaining element may, if desired, be countersunk in the straight edge or face 2 to perform the function of the screws 15.

After the parts as above described have 10 been assembled with the zero marks on the ring 6 in register with the proper index marks on the frame 3, a split ring 16 equipped with a bubble or spirit level 17 fitted in a protective housing 18, is slipped within said ring. 15 6. The straight edge 2 is now placed on a level surface, and the ring 16 is adjusted until the bubble in the spirit level 17 indicates horizontalism. The ring 16 is now 20 locked in position by threading between its ends an expanding or conical locking screw 19, which expands the ring and clamps it tightly in position. If the ring 16 should slip and come out of adjustment, it may be 25 readily returned to alinement as above described.

It is believed the construction of the device has been sufficiently set forth and that recapitulation is unnecessary other than to state that the adjustable or operating ring 30 6 is preferably formed on its opposite sides with a pair of outwardly projecting operating knobs or handles 20 by means of which the operator may readily set the tool to the desired position. It is to be understood that 35 while I have described and claimed the preferred embodiment of the invention, I reserve the right to make all changes properly falling within the spirit and scope of the appended claim.

40 I claim:

In an adjustable level the combination with a supporting frame-work having an annular casing, a straight edge carried by said frame-work, a grooved ring rotatively mounted in the casing, a clamping element carried by the casing and adapted to apply clamping action on the ring by engagement with the bottom of the groove therein, a guide carried by the casing and projecting into said groove, 45 a second ring rotatively mounted in the first named ring, means for maintaining said second ring against movement, and a spirit level 50 carried by said second ring.

In testimony whereof I affix my signature:
ARTHUR B. WALTERS:
